Primary Examiner — Rebekah A Caruso(74) *Attorney, Agent, or Firm* — Muncy, Geissler, Olds
and Lowe, P.C.(57) **CLAIM**The ornamental design for a supporting frame, as shown and
described.**DESCRIPTION**FIG. 1 is a perspective view of a supporting frame showing
the claimed design in an unfolded configuration;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is another perspective view showing the claimed
design in the unfolded configuration for supporting an
electronic device;FIG. 9 is another perspective view showing the claimed
design being in another unfolded configuration; and,FIG. 10 is another perspective view showing the claimed
design being in a folded configuration.The broken lines in FIG. 8 are directed to environment and
are for illustrative purpose only, while all other broken lines
depict portions of the supporting frame; the broken lines
form no part of the claimed design.**1 Claim, 10 Drawing Sheets**(56)
